UNITED STATES PATENT OFFICE.

FREDERICK HENRY BERGMAN, OF NEWTON, IOWA.

MECHANICAL MOVEMENT FOR WASHING-MACHINES.

1,208,273.

Specification of Letters Patent. Patented Dec. 12, 1916.

Application filed February 9, 1916. Serial No. 77,150.

To all whom it may concern:

Be it known that I, FREDERICK HENRY BERGMAN, a citizen of the United States, residing at Newton, in the county of Jasper and State of Iowa, have invented certain new and useful Improvements in Mechanical Movements for Washing-Machines, of which the following is the specification.

This invention relates to gearing for washing machines and particularly to a gearing whereby a combined and reciprocatory and rotary motion is given to the pounder head of such machines in combination with a periodic reversal of the latter motion.

It is well known that the washing action of pounder washing machines consists in forcing water and suds back and forth through the wash by alternating pressing and releasing them. This I have discovered is materially improved if the pounder be rotated so as to act upon different regions of the clothes and prevent them from sticking against the pounder and be still further improved if the pounder be periodically reversed in its direction of rotation.

The object of this invention therefore, is to provide simple, economical and efficient means for reciprocating, rotating and periodically reversing the pounder head of a washing machine or the like.

Other objects and advantages of the invention will appear as the description to follow proceeds.

In the drawings: Figure 1 is an elevation of a washing machine constructed according to my invention. Fig. 2 is a plan view thereof. Fig. 3 is a detailed cross sectional view of a portion thereof. Fig. 4 is a plan view, partly in cross section of the reversing mechanism. Fig. 5 is a similar view showing parts in the pawl portion of the operating mechanism. Fig. 6 is a sectional view of the reversing pawl and associated mechanism. Fig. 7 is a perspective view of the pawl. Fig. 8 is an elevation of a portion of the crown ratchet forming a part of the operating mechanism.

In the drawings 1 represents, in general, a washing machine tub provided with a hinged cover, these parts being old and well known. Mounted upon a hinged cover 2 is a plate 3 having a bushing 4 projecting into an aperture through the cover and a double standard 5, the plate 4 being secured to top of cover by bolts such as 6. Revolubly mounted in the bushing 4 is the extended hub 7

of a crown ratchet 8 having thereon one or more, in this instance one large rounded tooth 9, occupying the space occupied by two normal teeth. The hub of the crown ratchet 8 is provided with a square aperture in which is mounted a square shaft 10 carrying at its lower end a pounder head 11. Firmly bolted upon the plate 3 is a casing or cover 12 extending part way around the crown ratchet as shown in Fig. 4 and having upon its upper face a cup shaped depression terminating in an angular shoulder 13, seated against a cutaway portion of the hub 8 of the crown ratchet, thus preventing the crown ratchet from being raised during the reciprocation of the shaft 10 as hereinafter explained. The cover plate 12 is provided with a segmental extension 14 as shown in Fig. 2, to cover and protect the operating gear mechanism to be described. Upon the cover plate 12 is a closed tubular extension 15, surrounding the upper part of the shaft 10, which shaft is provided with a rounded upper end 16, projecting through the top of extension 15 and provided outside of said extension with a cotter pin 17.

Partially mounted in the double standard 5 is a casting 19 provided with a rigid arm 21 to form a bell crank lever and with a handle 20. The arm 21 is widened and forked at its end 22 to permit the upper end of the shaft 10 to pass between the branches of the fork and at its end is pivotally connected with links 23 which are in turn connected with the member 15. It will be seen that oscillation of lever 20 will result in vertical reciprocation of shaft 10. Pivotally connected with the lower end of the casting 19 is a bent link 24, which is forked at its outer end and is pivotally engaged with a pin 25 vertically mounted in a segmental upright flange 26, integral with a horizontal plate 27, terminating in a collar 28, surrounding the bushing 4 of the plate 3. The flange 26 is extended in both directions as indicated, to overlap at both ends the vertical portion of the casing 12 and so completely inclose the crown ratchet 8. Pivotally mounted upon the pin 29 in the flange 28 is a pawl 30, having double blades 31 and 32.

It will be obvious that operation of the handle 20 will serve to reciprocate link 24 and thus oscillate the flange 26 about the shaft 10 and by means of the pawl 30 cause the intermittent rotation of this shaft through the agency of the crown ratchet 8.

The crown ratchet 8 will continue to be turned in the same direction until the large tooth 9 thereupon comes up against the outer rounded face of the pawl 30. The next return stroke of the pawl 30 will cause the outer rounded face of said pawl to ride up upon the large tooth 9, which is made rounded as shown, throwing said pawl over its pivot to the outer side and reversing its action upon the crown ratchet 8, so that the direction of rotation of the crown ratchet 8 will be reversed until such time as the large tooth 9 again impinges the tooth 9, whereupon another reversal will occur and so on.

In operation, the handle 20 is oscillated which serves to vertically reciprocate the shaft 10 and therefore cause the pounder to act upon the clothes in the wash tub. At the same time the shaft 10 will be rotated and periodically reversed through the agency of the crown ratchet 8. The spring 18 serves to hold the parts at one extreme of their stroke and increases the pounding action upon the clothes by adding to the force by which the pounder is dropped each time.

I claim:

1. In a gearing for washing machines or the like, a support, a reciprocatory shaft in said support, means to rotate said shaft during the reciprocation including means to periodically reverse the direction of its rotation after it has rotated in one direction during a plurality of reciprocations.
2. In a gearing for washing machines or the like, a support, a reciprocatory shaft in said support, means to reciprocate said shaft, connections from said means for intermittently rotating said shaft, including means for periodically reversing its direction of rotation.
3. In apparatus of the class described, a support, a member hinged to the support, a standard on said member, a lever pivoted

in said standard, a reciprocatory shaft in said hinged member, connections between said lever and said reciprocatory shaft for operating the latter both in longitudinal and rotary directions including resilient means for holding the shaft in extended position.

4. In apparatus of the class described, a support, a member hinged to the support, a reciprocatory shaft in said member, a ratchet slidably but non-rotatably mounted on to said shaft, means including a bell crank lever and a link for reciprocating the shaft, means operated by said bell crank lever for rotating said ratchet, including a reversible pawl.

5. In an apparatus of the class described, a support, a member hinged to the support, a reciprocatory shaft in said member, a ratchet slidably but non-rotatably mounted on to said shaft, lever operated means for operating said shaft, connections from said lever operated means for rotating said ratchet including a two edged pawl and a projection on said ratchet to periodically upset said pawl and thereby reverse the direction of rotation of the ratchet.

6. In apparatus of the class described, a support, a member hinged to the support, a reciprocatory shaft on the hinged member, a crown ratchet surrounding the shaft, a pawl operating upon said crown ratchet to rotate the reciprocatory shaft, means for operating said pawl, a casing surrounding a portion of said ratchet, and a guard connected to said pawl and adapted to complete the inclosure of said ratchet to protect the same, substantially as described.

In witness whereof, I hereunto subscribe my name to this specification in the presence of two witnesses.

FREDERICK HENRY BERGMAN.
